ELECTRIC WASHING MACHINE

Earl S. Burdick, Milwaukie, and Charles R. Thomson, Portland, Oreg., assignors to Klosterman Inc., Portland, Oreg.

Application December 20, 1930
Serial No. 503,780

1 Claim. (Cl. 68—18)

This invention relates generally to machines for washing clothes, and particularly to an electrically propelled machine of small dimensions as compared with the ordinary machine of the household type.

The main object of this invention is to provide a novel form of washing machine particularly adapted for small washings and for washing delicate fabrics.

10 The second object is to construct a machine which will be exceedingly simple to manufacture and assemble and which will be quiet in operation and also extremely durable in service.

These, and other objects, will become more apparent from the specification following as illustrated in the accompanying drawings, in which:

Fig. 1 is a side elevation of the machine.

Fig. 2 is an end elevation.

Fig. 3 is a vertical section taken along the line 20 3—3 in Fig. 1.

Fig. 4 is a vertical section taken along the line 4—4 in Fig. 1.

Fig. 5 is a vertical section taken along the line 5—5 in Fig. 3.

25 Similar numbers of reference refer to similar parts throughout the several views.

Referring in detail to the drawings, there is shown a pair of end frames 10 and 11 which are held in spaced relationship by the rods 12.

30 Mounted between the frames 10 and 11 is a washing cylinder 13 whose end 14 is provided with a trunnion 15 which journals in the frame 10. The end 16 of the cylinder 13 is provided with an elongated trunnion 17 which has an opening 18 35 formed therethrough and a provision at its outer end 19 for a hose connection.

The trunnion 17 journals in the wall 20 of the frame 11, which differs from the frame 10 inasmuch as it forms a housing or gear case for the

40 operating mechanism. The frame 11 has formed therein an opening 21 provided with a cover plate 22 through which projects the end 19 of the trunnion 17.

On the wall 20 is mounted a motor 23 to which 45 energy is supplied through the cord 24. The motor 23 drives the shaft 25 through the flexible coupling 26. The shaft 25 carries a worm 27 which meshes with the worm wheel 28 mounted on a stud bolt 29 projecting from the side of the

plate 30 which is carried by the pillars 31, which are carried by the wall 32 which wall is spaced a short distance from the wall 20. The worm wheel 28 serves as a crank by means of which crank the connecting rod 33 imparts a rocking motion to the cylinder 13 through the lever 34 secured to the trunnion 17.

It is desirable to provide the cylinder 13 with a removable handled cover 35 and also a waste pipe 36, which is controlled by the small lever 37. The floor 38 of the frame 11 is provided with a drain opening 39 through which water from the waste pipe 36 can pass.

The operation of the device is as follows: 70 Clothes, water and a cleansing agent are placed within the cylinder 13 and the cover 35 is put into position (as shown in Fig. 5) after which current is supplied to the motor 23 which causes the worm wheel 28 to revolve, and, through the members 33 and 34, to rock the cylinder 13, which is incidentally provided with a number of ribs 40 and 41 for the purpose of bringing about a better tumbling action for the fabrics.

The washing operation can be continued as long as desired, after which the articles can be 80 removed with or without allowing the water to escape through the waste pipe 36.

It can be seen that by this construction an exceedingly simple and rigid form of machine is produced and one of such small weight as to 85 permit its selling through the mail, which is highly desirable with this class of merchandise.

We are aware that many forms of washing machines have been constructed in the past, and it is not our intention to broadly cover this invention; it is rather understood that we do intend 90 to cover all forms and modifications thereof as fall fairly within the appended claim.

We claim:

In a washing machine, the combination of a 95 pair of spaced side frames, one of said frames being hollow and having a catch basin formed therein, a rockable water cylinder mounted between said frames having an extending outlet projecting into said catch basin, and means within said hollow standard for rocking said container.

EARL S. BURDICK.
CHARLES R. THOMSON.
